METHOD AND MEANS OF DOUBLE GLAZING
WINDOW SASH AND DOORS

Carl J. Martinson, Wayzata, Minn.

Application February 17, 1932, Serial No. 593,488

4 Claims. (Cl. 20—56.5)

My invention relates to the method and means of double glazing window sash and doors so that the ordinary type of sash may be provided with an extra glass to double glaze the same and provide a means of preventing condensate or frosting on the windows in climates where the outer atmosphere becomes cold in the winter.

A feature of the method resides in forming a groove around the window sash for the pane of glass and by means of my stock molding members made after the pattern and formation of my invention securing the extra pane of glass in the window sash to provide the double glazing to seal the edges of the glass in the frame so that the air between the two panes of glass in the window sash is virtually hermetically sealed from the outer atmosphere, thereby making a dead air space between the windows. This dead air space between the windows provides an insulating means which prevents the inner window from frosting over or collecting condensate which is commonly known as steaming of the inside window-pane when there is a change in atmosphere between the inside and the outside. The invention includes the making of strips of molding with a cushion surface thereon made of rubber, cork, felt or other suitable material. The cushion surfaces of the molding are adapted to engage the edges of the glass in carrying out my method of double glazing of window sashes.

By stock molding I mean my new form of molding made after the construction described and as will be more fully hereinafter pointed out. The groove for the glass or molding can be readily formed in the ordinary type of window sash and then with my new stock molding having the cushioned glass gripping surfaces it will be very easy to change a single glazed window to a double glazed window and my moldings will seal the edge of the glass tightly so as to keep the dead air space between the two panes of glass in the sash after the same has been made over into the form of double glazing as defined by my method.

The double glazing may be accomplished in various manners to provide a means of insuring the sealing of the dead air space between the window-panes and so as to bring the window-panes and the double glazing more closely together where a narrow sash is desired, or the window sash may be made of a particular construction so as to receive the double window-panes when they are made up at the time of manufacture of the window sash.

My method also includes a means of embedding the edge of the glass in a cushion channel and

then securing the channel cushions around the edge of the glass firmly in place by my particular clamping means which will be later described, and then while the double windows are held by this cushion and clamping means the whole unit holding the glass together can be slipped into the window sash and anchored in place, thereby providing a double glazed window by my method of a very desirable nature.

All of the features and peculiarities of my method and means for carrying out the same will be clearly defined.

In the drawings forming part of this specification:

Figure 1 is a sectional view of the window sash, showing my method and means of double glazing the same.

Figure 2 is a perspective of a detail, showing the means of anchoring the window-pane for double glazing of the sash by my method and means.

Figure 3 is a section similar to Figure 1, showing another form of carrying out my method.

Figure 4 is a section of double glazed window sash, using my method.

Figure 5 illustrates a section of one of the window sashes, showing a further form of my means of double glazing of the same.

Figure 6 is still another form in section of a window sash, showing the double glazing as used in carrying out my method.

Figure 7 is a perspective, illustrating the construction of the unit binding for the double glazing of the window-pane as used in Figure 4.

Figure 8 shows a perspective of a window-pane having a single cushion channel around the marginal edge thereof as is used on each of the window-panes in Figure 3.

My invention consists in the method and means of double glazing window sash and doors, and the drawings illustrate the upper window sash 10 and the lower window sash 11 in section and as they would appear, excepting being partly broken away, in position in the window frame. The drawings will assist in describing the method employed to provide the double glazing such as is applied to the regular standard window sash 10 and 11, like in Figure 1, and to the window sash 10 and 11 illustrated in the other figures, where a particular construction is used to bind the marginal edges of the respective panes singularly or in double glazed position where a particular unit clamping means is employed to hold the double panes of glass together.

The window-pane 12 in the window sash 10 and 55

11 may be first anchored in the sash by dropping one edge into a groove 13 formed in one edge of the window frame where it is embedded in putty. The outer side of the glass pane rests against 5 a portion of the frame.

10 My method consists in forming the sash 10 and 11 around the remaining three sides of the window-pane on the inside with a glass and molding groove 14. This groove 14 is adapted to 15 accommodate the pane of glass 15, the glass pane 12, and the molding therebetween.

15 After the grooves 13 and 14 have been formed into the window sash 10 or 11, or the door frame which ever it may be desirable to double glaze, 20 an inner molding 16 with a cushioned surface 17 is secured in the groove 13. This cushion portion 17 may be provided with a lip 18 that may extend around the outer edge of the glass so that the glass may rest against the cushion and the lip 25 18 as shown by Figure 2. When the inner molding 16 formed with the cushioned surface 17 is in proper position, then the glass 15 is placed against the same, after which the outer and anchoring molding 20 is placed into the groove 30 14. This anchoring molding 20 may be formed so that it may extend flush with the inner surface of the window sash 10 or 11 when anchored in place, as illustrated in Figure 1. The molding 20 is formed with a glass cushioning and engaging 35 surface 21 which engages against the marginal edge of the glass and forces the same tightly against the cushion 17, thereby engaging the marginal edges of the glass between the cushions 11 and 21, and sealing the same about its marginal 40 edge. When the glass 15 is held adjacent to the outer glass 12 in the manner just described, the space 22 between the outer and inner window-panes becomes a dead air space, thereby insulating the inner glass from the outer glass. The 45 simple effective method of securing the inner glass by these sealing moldings which can be made so as to speak, a stock molding, permits any window sash to be double glazed by my method very readily. This method consists in forming a glass receiving groove in a window sash and also forming molding receiving grooves where it is necessary. Then the molding is placed in the glass receiving groove with the cushioning surface projecting outwardly and the glass laid against the 50 same, after which the anchoring and sealing molding is forced tightly against the marginal edge of the glass, thereby causing the sealing moldings to seal the edge of the inner glass in a manner to glaze the same in operative position to 55 provide a double glazed window structure of a weather resisting nature and retarding frosting or steaming in the collecting of moisture on the inner window-pane. This simple method provides a very practical means of double glazing of virtually any form of window sash. Suitable screws such as 24 may be employed to hold the molding 20 in position to firmly engage and hold the glass 15 in place.

60 Each pane of glass 12 and 15 may be held individually in a marginal binding or cushion member 25 and a single molding such as 26 used to squeeze or clamp the cushion portions 25 together against the shoulder molding 27 on the other side of the sash 10 and 11, as illustrated in Figure 3 65 of the drawings.

65 It may also be desirable to provide a unitary clamping means for holding the cushion portions 25 extending around the glass 12 and 15, like that illustrated in Figure 4, where an angle metal binding member 28 is employed. The member 28 is

70 formed with a central wire receiving groove 29 into which the binding wire 30 is adapted to extend. The member 28 is provided with side flanges 31 extending on either side of the central groove 29. After the cushion binding 25 has been 75 placed around the marginal edge of the glass 12 and 15, then the metal binder 28 is carried around the outer edge of the cushion portions 25 with the central portion of the member 28 acting as a separator, such as 32, to hold the panes of glass 10 80 apart and a groove 29 receiving the binding wire 30 which is drawn taut to hold the panes of glass 12 and 15 together as a unit. Then this unit is placed in the sash 10 and 11, as illustrated in Figure 4, after which a securing molding 33 85 15 is adapted to hold the unit in place in the sash. The flange members 31 are narrower than the width of the cushion members 25, thereby permitting the molding 33 to compress the cushion channels or binding 25 to hold the unit such as 20 B which is formed of the two panes of glass 12 and 15 and bound by the member 28, in the sash frame firmly and under tension.

90 The binding cushion such as 25 may be made in a single piece 34, illustrated in Figure 5, if it is desired. In this construction the clamping member 28 is the same as used in Figures 4 and 7 and the wire 30 holds the same in place to hold the unit B collectively secured together.

95 When the glass is supported in a unit such as B, if it is desired, either of the glass panes 12 or 15 may be made in smaller panes and held together by molding strips such as 37 and 38, the molding 38 being positioned between the panes of glass in the dead air space 22 and thus a window 35 40 may be formed with a series of panes connecting together or to divide the window up with molding in a very practical manner. The moldings 37 and 38 may be held together by screws or any other suitable means to clamp the same rigidly against the edges of the glass and the molding 38 may fit with a cushion member 39 resting against the glass 15 if it is desired, so as to hold the moldings 45 firmly in place and to brace the panes of glass 12 and 15, one in relation to the other, at a point spaced from the inner glass holding portion of the window sash such as 10 and 11.

50 An inner molding such as 40 may be employed to give the appearance of dividing the glass or unit B as illustrated in Figure 4, and a suitable cushion member 41 may be used to take up the inequalities between the window-panes 12 and 15 and hold the molding firmly between the two panes of glass so as to give the appearance of a divided window-pane, yet having a perfectly 55 smooth outer surface both on the inside of the window and the outside thereof. This permits cleaning of the windows without the objectionable features of having the moldings which divide the window into small panes.

60 In Figure 6 I illustrate a form of construction quite similar to that illustrated in Figure 1. In this structure, the outer glass 12 is embedded in putty in a groove 13 along one edge of the frame and bears against the shoulder portion 43 extending about the other three sides of the window frame. A molding strip 16' is adapted to bear against the inside of the outer pane 12 and a second pane 15 such as is illustrated in Figure 8, having a cushion edge extending thereabouts, 70 is adapted to bear against the molding strip 16'. The two window panes 12 and 15 are held in place by a molding strip 44 which may be held in place by nails 45 or in any other suitable manner.

75 Figure 7 illustrates two adjacent window panes 75

12 and 15, each provided with a resilient cushioning member extending along the edges thereof. Part of these cushions 25 have been broken away to show the construction thereof.

5 The advantages of my method and means of double glazing window sash and doors is of primary importance. It permits the double glass to be connected to the single sash, with the two panes of glass insulated one from the other so as 10 to overcome the differences in temperature on the inside and outside of buildings and to provide a storm window without the necessity of a storm sash in climates where it becomes extremely cold outside during the winter months. With 15 my simple effective means of binding the edges of the glass together or anchoring the same in a very inexpensive manner in the sash, double glazing may be accomplished wherein the windows are sealed one from the other and to provide a dead 20 air space 22 between the windows which is hermetically sealed and into which no dust or dirt can collect, therefore making it unnecessary to clean the glass on the inside. Should it ever become necessary to remove the glass this may be 25 accomplished very readily. Therefore, the glass may be easily replaced if broken or changed at any time should it be desired.

In accordance with the patent statutes, I have described the principles of my method and means 30 of double glazing window sash and doors and I desire to have the invention interpreted within the scope of the following claims.

I claim:

1. A double glazed window including, the main 35 window-pane, a window sash for supporting said pane, a complementary window-pane receiving groove, an auxiliary window positioned in said groove, a removable non-resilient spacing strip between corresponding edges of said panes, and means for binding the marginal edge with a cush-

ioning molding to hermetically seal the air between said window-panes to provide a double glazed window in a single sash.

2. A double glazed sash including, a main window-pane sealed and supported in said sash, 5 an auxiliary window-pane, cushion engaging means for the marginal edge of said auxiliary window-pane, a non-resilient removable spacing strip extending between said cushion and said main window-pane, and molding means for holding said cushion engaging means in a manner to press the marginal edge of said auxiliary glass into sealing position in said sash and to press said spacing strip against said main window-pane to provide a dead air space between said 15 window-panes.

3. The combination, a window and door sash, a window-pane fixed in said sash, an auxiliary window, marginal cushion sealing means adapted to extend about said auxiliary window, a non- 20 resilient spacing strip between said cushion means and said window-pane, and means for binding said sealing means with said auxiliary window adjacent said main window to hermetically seal the space between said windows. 25

4. The combination, a window sash, a window-pane fixed in said sash, an auxiliary window-pane, a groove for receiving said auxiliary window, a cushion tape extending on either side of said auxiliary window in said receiving groove, a removable non-resilient spacing strip extending between said cushion tape and said first named window-pane, and molding means for binding 30 said auxiliary window by compressing said cushion tape marginally about said auxiliary window and for pressing said spacing strip against said first named window-pane to hermetically seal the space between said window-panes. 35

CARL J. MARTINSON.
